Primary Examiner — Kelley Donnelly*(74) Attorney, Agent, or Firm* — Volpe and Koenig, P.C.(57) **CLAIM**

We claim the ornamental design for a plastic basket, as shown and described.

DESCRIPTION

FIG. 1 is a front, top, right perspective view of a plastic basket according to our design:

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom view thereof.

The broken lines represent unclaimed portions of the plastic basket and do not form part of the claimed design.
